UNITED STATES PATENT OFFICE.

JOHN E. MITCHELL AND DENNIS PARKS, OF ST. LOUIS, MISSOURI.

COMBINED LIFT-CUTTING AND HEEL-BLANK-BUILDING MACHINE.

1,157,409.

Specification of Letters Patent.

Patented Oct. 19, 1915.

Application filed November 2, 1914. Serial No. 869,740.

To all whom it may concern:

Be it known that we, JOHN E. MITCHELL and DENNIS PARKS, citizens of the United States, residing in the city of St. Louis and State of Missouri, have invented new and useful Improvements in Combined Lift-Cutting and Heel-Blank-Building Machines, of which the following is a specification.

This invention relates to certain new and useful improvements in heel building machines, and has particular reference to improving that type of machine illustrated in a certain application for patent of William Wolfe, filed August 17th, 1912, Serial Number 715,536. The said Wolfe machine comprises a revolving turret or carrier having a series of dies thereon which pass over a receiving mold. Means are provided for intermittently rotating the turret, for successively actuating the dies, and for discharging the lift cut by each die into the mold. The lifts in their passage to the mold are supplied with paste, and when a sufficient number of lifts have been deposited in the mold to form a heel of the desired height the lifts are nailed together and subsequently ejected from the mold.

One of the objects of the present invention is to construct a machine capable of carrying out the operations of the said Wolfe machine so far as cutting, pasting and depositing lifts in a mold or former are concerned, but which shall be much simpler in construction and operation; a further object of the invention is to provide for depositing the cut and pasted lifts in a holder of a length to accommodate a plurality of heel-blanks and of a size to frictionally engage them, and for separating each series of lifts deposited in the holder, and constituting a heel-blank, from the lifts subsequently deposited to form another heel-blank, whereby as the lifts are successively deposited in the holder and preceding lifts, or heel-blanks, will be forced downward therein, and, due to the frictional resistance of the holder, will be pressed firmly together and maintained under compression, while the length of the holder is such as to insure that the heel-blanks will thoroughly set before discharging from the bottom of the holder; a further object of the invention relates to novel means for separating the lifts deposited in the holder into series, each series of lifts constituting a heel-blank; a further object

of the invention is to provide for rotating the die turret independently of the power driving mechanism of the machine; a further object is to provide for centering, or accurately positioning, the lifts within the holder, or former; a further object is to provide novel mechanism for applying paste to the cut lifts; a further object relates to means for rendering the paste-applying device inactive at will; a further object is to provide a novel means for automatically rotating the cutting block; a further object relates to combining with the machine means for indicating the thickness of the lifts cut by the respective dies, so that the operator will be enabled thereby to make the heel-blanks of the same uniform height; and still further objects of the invention relate generally to details for construction, coördination and combinations of parts affecting the character and operation of the machine as a whole, all of which will be more clearly understood by the detail description following, and from the appended claims.

In the drawings—Figure 1 is a front elevation of a machine constructed according to our invention. Fig. 2 is a side elevation of the machine. Fig. 3 is a view partly in side elevation and partly in vertical section looking at the opposite side of the machine from that shown in Fig. 2. Fig. 4 is a plan view of the machine. Fig. 5 is a horizontal section taken substantially on the line 5—5 of Fig. 2. Fig. 6 is a fragmentary view showing the clutch mechanism. Fig. 7 is a detail view of the fixed member of the clutch, or that member secured on the driving shaft. Fig. 8 is a view showing in perspective the movable member of the clutch and the releasing device therefor in detached relation. Fig. 9 is a fragmentary view, partly in vertical section and partly in elevation, showing the mechanism for controlling the movement of the die carrier or turret. Fig. 10 is a section on the line 10—10 of Fig. 2. Fig. 11 is a detail view of one of the plates used for separating into heel heights the lifts deposited in the holder, or former, by the dies.

Referring now to the drawings the numeral 1 indicates, generally, the frame of the machine which, preferably, is made in a single casting in which all necessary bearings and supports are provided, and which parts will be referred to in detail as may be

required in the further description of the machine. The frame as a whole is shown supported on horizontally-disposed girders 2. The frame provides two side members 5 or standards 3, 4, which are integrally united by suitable webs with an upper bearing 5 and a lower bearing 6, for a column 7. The lower end of this column extends through the bearing 6 and rests upon ball 10 bearings 8 mounted on a race-way 9 which is adjustably secured by bolts 10 to the lower end of the bearing 6. The column 7 fits the guides 5, 6, closely but so as to rotate freely therein, said bearings, and especially the upper bearing 5, serving to center and support the column 7 to brace it against movement under lateral strain occasioned by the cutting operation, as will be referred to later on. Fixedly secured on the column 7 20 is a sleeve 11 which bears against the lower end of the bearing 5 and thereby prevents the column 7 from rising as the lifts are cut. Similarly secured on the column 7 near the lower end thereof is a sleeve 12 on the upper end of which, and preferably formed integral therewith, is a combined ratchet and stop wheel 13 which is actuated to rotate the column 7 in the manner to be later described.

Secured on the upper end of the column 7 30 is a die turret 14, comprising a hub 15 mounted on and keyed to the upper end of the column 7, extending radially outward from which hub are a series of equi-distant arms 16 having integral vertically-disposed flanges 17 and united by webs 18, the flanges 17 being united at their inner ends to form radial webs 19 which extend to and are integrally united with the hub 15. As shown 35 in the drawings, there are eight of the arms 16 and an equal number of pairs of the flanges 17 which form, as it were, a star wheel. Secured on the under side and toward the outer end of each of the arms 16 40 save one, is a die 20, which is preferably removably secured to the arm by angle-bolts 21 extending through the arm and through 45 the top of the dies and engaging in apertures in the sides thereof, and having nuts 22 applied to their upper ends, which by 50 being screwed home, maintain the die in fixed position on the under side of the arm. Projecting downward from the top of each die 55 is a sleeve 23 in which works a plunger 24 having an ejector 25 on its lower end, and provided at its upper end with a head 26, between which and the upper side of the arm 16 is located a coil spring 27. These 60 dies may be all of one size if desired, but preferably they successively increase in size, so that when the lifts cut thereby are assembled in order, they will form what is known as a "decked" heel, that is to say, a heel having tapering sides. Each of these dies 65 is located centrally between a pair of the

flanges 17. These flanges, however, and the webs 18 have no other function than to act as braces to the arms 16 to enable them to withstand the upward thrust of the cutting block, to be later referred to. Projecting 70 outwardly from the side 4 of the frame near the top thereof are two parallel struts 28 which at their outer ends are integrally united with a vertically-disposed bearing 29. Somewhat lower a similar pair of struts 75 30 project outward from the side member 4, and at their outer ends are formed integral with a vertically-disposed bearing 31, which is in alignment with the bearing 29. Mounted to reciprocate in the bearings 29 and 31 80 is a rod 32 on the upper end of which is adjustably mounted a sleeve 33 carrying a hammer 34.

The numerals 35, 36 indicate bearings provided on the respective side members 4 85 and 3 through and supported in which is the main driving shaft 37. This shaft has at one end an eccentric pin 38 on which is rotatably secured by a nut 39 a collar 40, adjustably secured to the lower end of a connecting rod 41. Fixedly secured on the rod 32 is a sleeve 42 formed integral with which is a projection affording a bearing for a head 43 secured to the upper end of the connecting rod 41, and held on such bearing by a nut 44. As thus far described it will be seen that as the shaft 37 is rotated the eccentric pin 38 will cause the connecting rod 41 to be reciprocated, which in turn will lower and raise the rod 32. Projecting outwardly 90 from the side frame member 3 are two bosses 45 and 46, respectively, located one above the other and provided with two sets of vertically-disposed alining apertures. In one set 95 of these apertures is rotatably mounted a rod 47 on the upper end of which is secured, as by means of a set screw 48 (see Fig. 3), a cup 49 in which is mounted a circular block 50, preferably of wood. The rod 47 with its 100 block is supported from the lower boss 46 by means of a collar 51 fixedly secured on the rod 47 and a coil spring 52 interposed between said collar and the top of the boss 46. Mounted to reciprocate in the other set 105 of apertures in the bosses 45 and 46 is a plunger rod 53, to the lower end of which is pivotally connected, as at 54, the upper end of a connecting rod 55, the lower end of which has a head 56 which is rotatably mounted on an eccentric pin 57 projecting 110 from the opposite end of the main shaft 37 to that first described, and being retained thereon by means of a collar 58 applied and secured to the outer end of said eccentric pin 57. The plunger 53 is disposed immediately under or in line with the position assumed by each of the dies 20 when brought to rest over the cutting block 50, and as the shaft 37 is rotated the plunger 53 will be caused to 115 be raised by the eccentric pin 57 and con-

necting rod 55 to raise the cutting block 50 so that leather or other material, such as indicated by the numeral 59, in Fig. 3, will be forced up against a die 20, and be cut by said die, after which operation the cutting block will drop to its normal position as the plunger 53 is lowered. In the event the leather or leather-board placed on the block 50 is slightly thicker than the space normally provided between the lower edge of the cutting die and the upper surface of the block 50, said block can be depressed by the operator pressing down thereon, the spring 52 yielding for this purpose.

In order to obviate having the dies 20 engage the upper surface of the cutting block continuously at the same point, provision is made for rotating the said block, but not positively. To this end a bell crank lever 60 is mounted on a stud 61 on the side of the boss 45, one arm 62 of said lever carrying at its outer end a friction head 63, which is held in normal engagement with an annular shoulder 64 formed on the bottom of the cup 49 by means of a coil spring 65, (see Figs. 2 and 3) connected at one end to the other arm 66 of said bell crank lever, said spring at its other end being secured to a stud 67 mounted on the side frame member 3. It will thus be seen that as the cutting block falls after being released by the plunger 53 it will move the lever 62 downward and consequently outward, and the frictional contact of the head 63 of said lever with the bottom of the cup 49 will cause the cutting block to be slightly rotated.

We will now describe the mechanism by means of which the column 7, with its die turret, is intermittently rotated from the shaft 37. Rotatably mounted on the rear end portion of the shaft 37 is a pulley 68 which is continuously driven by a belt, not shown. The pulley 68 has a hub 69 in an aperture in which is slidably mounted a pin 70 which is carried by a clutch ring 71, which in turn surrounds and is slidably mounted on a reduced portion 72 of the hub. Fixedly secured on the extreme end portion of the shaft 37 is a fixed circular clutch member 73, having a hub 74 through which and the shaft 37 extends a pin 75 for securing said clutch-member to the shaft. In the inner side of the fixed clutch-member 73 there is provided a circular groove 76, (see Fig. 7) one end-portion of which is inclined, as indicated at 77, to provide for the gradual entrance of the pin 70 into said slot in the operation of the clutch, and the other end 78 of which constitutes a shoulder to be engaged by the pin 70 so as to rotate the fixed member 73. Pivotally mounted in the lower portion of the side frame members 3, 4, is a treadle shaft 79, having a treadle 80 secured on one end thereof in the usual way. On the other end of said treadle shaft

79 is fixedly secured a sleeve 81 projecting from opposite sides of which are arms 82, 83. The arm 83 is provided on its upper side at its outer end with a lug 84, which is formed on its inner side with an inclined or cam surface 85, and with a plane surface 86, which is flush with the side of the arm. The arm 82 is provided in its outer end with an aperture 87 in which is secured an eye bolt 88 having one end of a coil spring 89 secured thereto, the other end of said spring being connected to a plate 90 secured on the end of one of the girders 2 supporting the machine. Coil springs 91 (see dotted lines in Figs. 2 and 3) secured at opposite ends, 80 respectively, to the clutch ring 71 and the pulley 68 tend normally to draw said clutch ring toward the inner face of the pulley so as to cause the free end of the pin 70 to project beyond the outer face of the hub 85 69 to engage in the groove 76. This tendency of the springs, however, is normally prevented by the engagement of the plane surface 86 of the lug 84 behind the said clutch ring, as shown by Fig. 6. Projecting 90 radially outward from the clutch ring 71 is a lug 92 corresponding with the lug 84 and provided likewise with an inclined or cam surface 93 and a plane surface 94. The cam surfaces 85 and 93 are opposed to each 95 other, and in the rotation of the clutch ring 71 are designed to engage each other. When it is desired to start the machine in operation the operator presses down on the treadle 80 which rocks the shaft 79 and thereby 100 turns the lug 84 to a position below and out of engagement with the ring 71 which is then ready to be drawn inward against the pulley 68 by the springs 91 as the pin 70 is brought by the rotation of the pulley 68 105 opposite the groove 76. When the pin passes into this groove it will move into engagement with the end 78 of the groove and thus cause the fixed number 73 of the clutch to be rotated in unison with the pulley 68 110 and clutch ring 71. When the operator releases the treadle the spring 89, against the resistance of which the treadle was pressed down, exerts its pull on the arm 82 to turn the shaft 89 and raise the lug 84, 115 the upper surface of which will engage and ride upon the periphery of the ring 71, as shown by dotted lines in Fig. 9. This movement continues until the lug 92 engages the lug 84, and as the incline 93 rides over the 120 incline 85, the ring 71 will be drawn outward, thereby withdrawing the pin 70 from the slot 76, so that the shaft 37 is no longer positively driven, and the plane surface 94 of the lug 93 will pass upon the plane surface 86 of the lug 84. The spring 89 will then act to throw the lug still farther upward to cause it to engage behind the clutch ring and hold it in its retracted position, this latter position of the parts being shown 130

in Figs. 3 and 6. A stop 94^a limits the downward throw of the arm 82 and consequently the upward movement just described of the lug 84. Formed integral with the sleeve 42 (Figs. 2 and 3) is a yoke 95 toward the outer end of which is connected one end of a coil spring 96. The other end of said spring is adjustably connected with one arm 97 of a bell-crank lever 98, which is pivotally mounted at 99 on the side of the bearing 6 (see also Fig. 9). The other arm 100 of the bell-crank lever is recessed (see Fig. 5) and in said recess is pivotally mounted a tongue 101 which is normally pressed inward or toward the ratchet wheel 13 by a leaf spring 102 secured in the recess of said arm.

The ratchet wheel 13 has projecting upward at regular intervals from its upper side a series of teeth 103, each of which has its outer surface inclined, as indicated at 104, and the tongue 101 is bent inward at right angles at its upper end to form a ratchet 105 which has its inner side inclined, as indicated at 106, to slide over the inclines 104. Pivotally connected to the outer end of the yoke 95 by a pin 107 is the upper end of a rod 108, the lower end of which has a slotted head 109, the slot of which receives a pin 110 secured intermediate the ends of the arm 97 of the bell-crank lever 98, (see Fig. 2). As the shaft 37 is rotated in the manner previously described the eccentric pin 38 draws the rod 41 with the yoke 95 downward, thereby causing the rod 108 to be pushed downward, in which movement the slotted head engages the pin 110 and turns the arm 97 downward, causing the tongue 101 to be drawn backward until the incline of the ratchet 105 has passed off of the incline of one of the teeth 103, when the spring 102 immediately snaps said tongue inward and causes the ratchet to engage behind a tooth 103, as shown in Fig. 5. As the shaft 37 completes its rotation the rod 41 will be moved upward by the eccentric pin 38, carrying the rod 108 upward, thereby releasing pressure on the arm 97 and permitting the spring 96 to exert its tension to raise the arm 97 and thereby move the tongue 101 in the reverse direction to that previously described, whereby the engagement of the ratchet 105 with one of the teeth 103 will cause the ratchet wheel 13 and the shaft 7 to be revolved to rotate the turret and bring another or succeeding die over the block 50.

In order to stop the rotation of the turret when each die in turn has been brought in the proper position over the cutting block 50 and a die on the opposite side of the turret over the holder hereafter to be described, the following mechanism is provided: The periphery of the ratchet wheel 13 is provided at regular intervals with rectangular

recesses 111, (see Fig. 3) each recess being located between two of the teeth 103. Pivotally mounted intermediate its ends on a shaft 112, which in turn is pivotally and adjustably mounted on screw bearings 113, located in the respective frame members 3 and 4, is a yoke 114, having at its upper end a tongue 115 which is adapted to engage in the recesses 111 of the ratchet-wheel 13. The yoke 114 has an integral downwardly-projecting arm 116 on the lower end of which is pivotally mounted at 117 one end of a dog 118. The free end of this dog (Fig. 9) is provided with a shoulder 119. Secured on the treadle shaft 79 (see Figs. 80 2, 3 and 9) is a sleeve 120 which has an integral upstanding arm 121 provided at its upper end with a head 122, which is adapted to be engaged by the shoulder 119 in certain positions of the parts. Secured to the free end of the dog 118 is one end of a chain, or other flexible connection, 123, the other end of which is connected to the arm 97. In the normal position of the parts the dog 118 is in an elevated position relative to the head 122, such position of the parts being shown in Fig. 2 and by the dotted lines in Fig. 1. When the treadle 80 is depressed the arm 121 is turned inward to the position shown in Fig. 9, and when the yoke 95 descends in the rotation of the shaft 37, the lowering of the arm 97 caused thereby permits the outer end of the dog 118 to fall so that when the operator releases his foot from the treadle the head 122 will engage the shoulder 119. The spring 89 now exerts its pressure to draw the arm 82 downward and thereby rock the treadle shaft 79 to raise the treadle, this movement of the treadle shaft moving the arm 121 outward, which movement, in turn, through the engagement of the head 122 with the shoulder 119 pulls the dog 118 forward, and causes the yoke 114 to be swung outward on the pivot 112, thereby releasing the tongue 115 from engagement with a recess 111 of the ratchet wheel 13. Immediately thereafter the rod 41 starts its ascending movement, and as previously described, permits the spring 96 to draw the arm 97 upward, whereby to rotate the column 7 and revolve the turret. As the arm 97 moves upward it raises the dog 118 and releases engagement of the shoulder 119 with the head 122, thereby permitting the spring 89 to rock the treadle shaft 79 to bring the treadle 80 to normal position, and also leaving the yoke 114 free to be moved inward against the ratchet wheel 113. This latter movement of the yoke is accomplished by a coil spring 124 (see Fig. 3, and the dotted lines in Figs. 1 and 9), one end of which is connected to the yoke, and the other to the frame of the machine. This spring operates to draw the tongue 115 against the periphery of the ratchet wheel 130

so that as soon as one of the recesses 111 moves under said tongue, the latter will at once snap into the same and prevent further rotation of the turret. This stopping of the 5 rotation of the turret is accomplished with practically no jar or noise, as the column 7 is not positively driven, but is turned solely by the action of the spring 96. In order to prevent any back-lash with consequent strain 10 on the yoke 114 and its bearings, we pivotally mount on the frame in bearings 125 (see Fig. 3) a horizontal dog 126, which is normally pressed inward by a leaf spring 127, the free end of said dog being always 15 in position to enter one of the recesses 111 and engage the forward wall thereof coincident with the entrance of the tongue 115 into the adjacent recess 111. When the clutch members are disengaged, the rotation of 20 shaft 37 is stopped by means of a friction-brake 127.

In the machine forming the subject-matter of the Wolfe application above referred to, molds are provided, each of which accommodates the lifts for a single heel; and in practice, the compiled lifts, or heel 25 blanks, after removal from the machine would be placed in a flat press, and there held under pressure until the paste between 30 the lifts had dried. According to the present invention provision is made for accommodating a number of series of compiled lifts, or heel blanks, in a single relatively long holder, or guide, in which each heel 35 blank is separated from the succeeding superimposed heel blank. The size of the said holder or guide is such that its walls will be frictionally engaged by the edges of the largest lift of each heel blank, so that considerable pressure is required to force the heel 40 blanks downward therein, the result being that the latter are automatically maintained under sufficient pressure to insure the firm 45 cementing of the lifts to each other, and thus the operations of molding or forming, pressing and drying the heel blanks are performed in a single device, and are incident to a single operation, viz., that of depositing 50 the pasted lifts in the said guide or holder. The said guide or holder comprises a fixed vertical member, or breast-plate, 128 (see Fig. 5), and a movable member 129, which is curved to conform to the curvature of the lifts, said curved member or back-plate 55 129 being held in yielding relation to the breast-plate 128 by means of a vertical series of coil springs 130 interposed between the rear side of said back-plate and vertical recessed bars 131. The breast-plate 128 and back-plate 129 are located within the struts 28 and 30, and extend through the same, as shown by Fig. 2, and mounted in these struts are adjusting screws 132, the screw-threaded 60 ends of which engage in the vertical bars 65 131, so that by turning said screws to bring

the bars 131 nearer to or farther from the breast-plate 128, the pressure to be exerted by the back-plate 129 through the medium of the springs 130 on the lifts inserted between the two plates may be increased or diminished, as the circumstances may require. The said breast-plate and back-plate as arranged and described form a holder for the superimposed series of compiled lifts, as will be clearly seen from an inspection of Fig. 3.

For the purpose of correctly positioning the lifts in the holder we provide the following mechanism, referring particularly to Figs. 1, 2 and 3. Mounted on either side 80 of the strut 28 is a plate 133 (see Figs. 2 and 10), each of said plates providing parallel bearings 134 in and between which is pivotally mounted a hub 135 formed integral with the lower end of a presser-bar 85 136. Each of said presser-bars has at its lower end a short arm 137 which is apertured to receive the bent upper end of a rod 138, said rod passing downward through and working in an apertured lug 139 formed 90 on the outer face of either side of the yoke 95. Adjustably secured on the rod 138 is a stop 140, and between said stop and the lug 139 is mounted a coil spring 141. Below the lug 139 the rod 138 has adjustably secured thereon a stop 142. As the yoke 95 is carried down by the rod 41 the lug 139 engages the stop 142 and draws the rod 138 downward thereby throwing the presser-arm 136 outward. When the yoke 95 raises 100 the lug 139 engages the lower end of the spring 141, and moves the rod 138 upward, causing the presser-arm 136 to be moved inward. On the upper end of each of the presser-arms 136 is pivotally mounted a former 143 which may be adjusted to various angles according to the incline of the heel being built, and as the presser-arms move inward these formers engage the lifts deposited in the holder and force them to the 110 correct position therein, and to the correct position with respect to the lift on which the lift thus adjusted has been deposited. The formers 143, operating as described, secure the proper lateral adjustment of the 115 lifts. It is next necessary to insure that all of the lifts shall have their breasts forced against the breast-plate 128, to secure the proper vertical alinement thereof. To accomplish this a bell-crank lever 144 is provided which is pivotally mounted at 145 on the frame of the machine, and has a long arm 146 bent at right angles to provide a hammer 147 which is positioned to pass through a recess 148 (see Fig. 3) formed 125 in the upper edge of the back-plate 129 to engage the rear edge of the lifts inserted in the holder. Pivotally mounted on the strut 28 is a dog 149 provided with a shoulder 150. On the arm 146 is mounted a stop 130

151 which is adapted to be engaged by the said shoulder. The numeral 152 indicates the other arm of the bell-crank lever 144 which is relatively short, and has connected near its outer end one end of a coil spring 153, the other end of which is secured to the frame of the machine. The spring 153 normally exerts its tension to raise the short arm 152 of the bell-crank lever to throw the hammer head 147 inward, or to the position shown in Figs. 2 and 3. Mounted on the short arm 152 is a stop 154. Extending upward from the inner end of the yoke 95 is an arm 155 which is provided with a shouldered end 156 adapted to engage the stop 154, and with an upward extension 157 adapted to engage the underside of the dog 149 to lift the same.

In the operation of the machine as the yoke 95 descends the shouldered end 156 engages the stop 154 and carries the outer end of the arm 152 downward against the resistance of the spring 153, thereby throwing the long arm 146 outward and permitting the shoulder 150 to fall behind the stop 151. In the upward movement of the yoke 95 the presser-arms 136 are first forced inward in the manner above described, after which the extension 157 raises the dog 149 to release the stop 151, and the spring 153 then exerts its power to throw the long arm 146 inward so that the hammer 147 is caused to strike the deposited lift with a sudden blow and drive it against the face of the breast-plate 128. The arrangement, as shown in the drawings, is intended more particularly for positioning lifts for a "decked" heel, that is, a heel in which each lift deposited is smaller than the preceding lift. The same arrangement, however, can be used for making a perfectly straight heel by simply adjusting the formers 143 so that their inner faces will stand perpendicular when in the position shown in Fig. 1, that is to say, the position in which they are against the lifts, no other adjustment of the parts being necessary.

In order to separate each series of compiled lifts constituting a heel blank from the succeeding lifts to be deposited, metal plates 158 are provided of the general shape of a lift, each of which is provided on either side and at its rear, respectively, with recesses 159, which are for the purpose of permitting the hammer 147 and the formers 143 to engage the lifts, as without these recesses these parts would simply strike against the edge of the plate. In practice, when a sufficient number of lifts to form a heel have been inserted in the holder, a plate 158 is then inserted on the topmost lift of the heel blank, the succeeding heel blank is then built up, and another plate inserted, and so on, this arrangement being illustrated in Fig. 3. In order to provide

for depositing these plates a carrier 160, similar in general configuration to one of the dies, is mounted on the under side of the turret, said carrier having two opposite pivoted sides 161, having inwardly-extending bottom edges 162 projecting somewhat below the two stationary sides of the carrier. The two stationary sides of the carrier have centrally-disposed lugs 163 projecting downward so that their under sides are flush with the under sides of the pivoted side member 161, the lugs 163 acting as guides. Coil springs 164 serve to normally hold the pivoted sides 161 against the stationary sides of the carrier. Mounted in the carrier 160 is a spring-pressed plunger 165 similar in all respects to the plunger 26. The carrier 160 is located to follow the die which cuts the last lift to be deposited to form a heel blank. Preferably a number of the plates 158 are placed in the pocket formed by the webs 16, immediately over the carrier 160, so that as the said carrier comes opposite the operator it serves as notice to him to insert a plate. This is done by the operator taking one of the plates and applying one of its edges to the lower end of one of the sides 161 and pressing it outward, and then pushing the other edge of the plate behind the lower edge of the other side, the plate, of course, being inserted between the guides 163. This can be done very quickly, and when the operator releases the plate 158 the springs 164 draw the sides 161 inward and about its front and rear edges. When the carrier 160 comes to a position over the heel-blank holder the plunger 165 will be operated by the head 34 to force the plate out of the carrier and deposit it upon the compiled lifts in the said holder.

For applying paste to the lifts the following mechanism is provided: On one side of the yoke 95 and near the inner end thereof is located a stop 166 (see Fig. 3). Pivotally mounted at 167 intermediate its ends is a lever 168, one end of which is in the path of the stop 166. The other end of said lever is provided with an apertured head 169. The numeral 170 indicates a jointed extension of the lever 168, said extension having an apertured boss 171 corresponding with the head 169, and through said boss and head extends a pin 172, a coil spring 173 being located between the head of the pin 172 and boss 171, and a second spring 174 between the head 169 and nuts 175 applied to the opposite end of said pin. The free end of the extension 170 is pivotally connected to a link 176, the upper end of which is pivotally connected to a rod 177. Projecting outward from the frame is an arm 178 provided at its outer end with a holder 179 for supporting the paste pot 180. Connected to the rod 177 is an arm 181 which

is bent, as shown in Fig. 1, to extend over and vertically into the paste pot 180, and therein has a horizontal extension 182 on which is mounted a dauber 183. The rod 177 extends upward through an aperture, (not shown), in the arm 178, which serves to guide it vertically, as will be understood. In operation as the yoke 95 descends the stop 166 engages the end of the lever 168 forcing it downward, thereby raising the link 176 and the rod 177, which in turn raises the bent arm 181 and the dauber 183, which latter will apply paste to the under side of the lift in the die 20 immediately over the paste receptacle 180. This occurs while the die is stationary, as the turret 14 is not caused to revolve until the yoke 95 is raised by the rod 41, as previously described. It is necessary to prevent applying paste to the under side of the first lift cut and also to the under side of the plates 158. To accomplish this we secure on the under side of one of the arms 16 immediately behind the first die 20 a stud 184, and in like manner in the arm 16, immediately behind the carrier 160, a similar stud 185. In the ordinary operation of the dauber the lever 168 and extension 170 move together as a single member. When the first die 20, or the carrier 160 is over the paste pot, however, the bent arm 181 will engage the stud 184 or 185 and prevent the dauber from coming in contact with the lift or the plate 158, as the case may be, the springs 173 and 174 yielding to permit the lever 168 to complete its throw.

The numeral 186 (see Figs. 1 and 3) indicates, generally, a device for use in adjusting the dies on the turret in the correct position, but as the same is not herein claimed it is considered unnecessary to describe the same, or its operation, in detail.

In order to prevent an operator from depressing the treadle 80 a second time before the machine has completed its cycle of movements occasioned by the first depression of the treadle, we provide on the sleeve 20 a lever arm 187 to which is pivotally connected the lower end of a safety-rod 188 (see Fig. 2). The safety-rod 188 passes upward through an aperture in a web 189 and through a similar and alining aperture provided in a lug 190, which latter is located relatively close to the under side of the ratchet wheel 13. The under side of said ratchet wheel is provided with a series of apertures 191 (shown only by dotted lines in Fig. 5) located, respectively, under the teeth 103, and one of which apertures normally lies directly over the upper end of the safety-rod 188. When the treadle is depressed the rod 188 will be raised by the lever arm 187 and its upper end pass into one of the apertures 191 in the ratchet wheel.

When the operator removes his foot from

the treadle the end of the rod 188 will be withdrawn from the aperture in the ratchet wheel, and the latter will subsequently be rotated. Should the operator again depress the treadle before the movement of the ratchet wheel has been completed, the end of the safety-rod 188 will simply strike against the under side of the ratchet wheel and no effect whatever will be produced.

The means for indicating the thickness of the lift cut comprises an arm 192 which is pivoted at its inner end at 193 on the bearing 29, and is provided substantially centrally of its length with an adjusting screw 194, the lower end of which screw rests on the top of the column 7 (see Figs. 2 and 3). The outer end of this arm has mounted thereon a head 195, in which are mounted a plunger 196 and a pin 197, the latter carrying an indicator 198 which is adapted to move over the face of a gage 199 (see Fig. 1). The plunger 196 is freely movable in the head but the pin 197, while movable, is maintained in frictional contact with the head so that it will remain in any position to which it is moved. Pivotally mounted at its inner end on the upper end of the plunger 196 is a dog 200 having an aperture 201 loosely surrounding the pin 197, and its outer free end being weighted, as indicated at 202, so that the bottom edge of the aperture at one side and the top edge at the other will "bite" or engage the pin 197. By turning the adjusting screw 194 the arm 192 can be raised or lowered so that the lower end of the plunger 196 will just clear the top of the heads 26 of the plungers 24 as the turret revolves. As the turret comes to rest, a head 26 will be immediately under the plunger 196. As the lift is cut the head 26 will be raised a distance corresponding with the thickness of the lift cut, and the plunger 196 will be raised a corresponding distance. In this movement of the plunger the dog 200 will be raised, and by reason of the engagement of the top and bottom edges of the aperture 201 with the pin 197 will raise said pin and its indicator 198. As the turret is again revolved the head 26 will move from under the plunger 196, and the latter will at once fall, this movement turning the edges of the aperture 201 momentarily out of engagement with the pin 197 and allowing the dog 200 to slide downward over said pin. The latter, however, will remain in the position to which it has been raised. This operation is repeated as succeeding lifts are cut, and by observing the indicator 198 the operator can, by selecting the appropriate thickness of leather, make all of the heel-blanks of the same height.

The general operation of the machine is as follows: The operator places a sheet of leather or leather-board on the cutting block 50 and under a die 20, and presses down on

the treadle 80. This operates the clutch mechanism in the manner described in detail above, and the plunger 53 is raised, engaging the under side of the cup 64 and 5 pressing the block 50 upward into engagement with the die, which latter cuts through the material on the block. Assuming that other lifts have been cut in a similar manner, and that, as shown by Fig. 3, a die 10 containing a cut lift is immediately over the heel-blank holder, at the same time as the plunger 53 is raised to cut a lift the rod 32 will be drawn downward by the connecting rod 41, causing the hammer 34 to engage 15 the head 26 of a die-plunger to depress the latter and force the lift into the holder. It will be understood, furthermore, that in the rotation of the turret each die is brought to a position directly over the paste pot 180, 20 and that each lift, except that in the first die, will have paste applied to its under side before it is moved to a position over the holder. As each lift is deposited in the holder it is forced down with considerable pressure 25 upon the preceding lift, the preceding lift or lifts being thereby forced downward in the holder. The above operations, that is, the cutting of the lift and the depositing of a previously cut lift in the holder, occur 30 during the downward movement of the rod 41 and yoke 95. Immediately thereafter these last-named elements are raised by the eccentric pin 38, which movement causes the presser-arms 136 to be forced inward, and 35 raises the dog 149 to release the arm 146, which then is thrown inward by its spring 153, these latter operations causing the deposited lift to be correctly positioned in the holder, as previously described in detail. 40 When each die in turn has been caused to deposit its lift in the holder, the plate-carrier 160 will then be turned to a position over the heel-blank holder, and the plate 158 previously inserted in said plate-carrier will 45 be forced out of the same by the hammer 34 engaging its plunger 165 and deposited in the heel-blank holder, as clearly illustrated in Fig. 3. These plates, as will be seen, separate the heel blanks, and as the process 50 continues the said heel blanks will be forced gradually downward in the heel-blank holder, the lowest or first lift of each heel blank engaging the breast-plate 128 and the back-plate 129, due to the pressure of the 55 latter plate on the lift caused by the springs 130, to offer considerable resistance to the downward movement of the heel blanks. This insures that each lift shall be applied to the preceding lift with a requisite amount 60 of pressure and caused to be firmly united thereto, and such engagement of the largest lift of each heel blank with the walls of the holder tending to prevent any tendency of the lifts in the heel blank beneath it to 65 expand as the pressure of the ejector 25 is

removed therefrom. We thus secure the important advantage, in a single operation, of forming or molding the heel blank, placing the same under pressure, and maintaining such pressure for a sufficient length of time 70 to permit the paste between the lifts to set. When the machine has been in operation a sufficient length of time, as the heel blank is completed in the top of the holder a complete heel blank, with the lifts thoroughly 75 united and in the desired dry state, will be ejected from the lower end of the holder. 80

The mechanism for causing the intermittent rotation of the turret has been previously described in detail, and it is believed 85 it is sufficient at this point to state that the operation and adjustment of the parts described is such that after each lift is cut the turret 14 will be revolved to bring a die over the block 50, another die over the paste pot, and a third die over the heel-blank holder; and that the turret remains in a stationary position while a new lift is being 90 cut, paste applied to the under side of the lift in the die over the paste pot, and the lift in the die over the heel-blank holder ejected therefrom and forced into said holder. As will be understood from the foregoing, the machine is operated at will by pressing down upon the treadle 80, and is automatically 95 stopped by the mechanism heretofore described, and in such manner that each die in turn is brought to a stop over the cutting block, paste pot, and heel-blank holder, and when the turret is brought to a stop, a die 100 is always over each of the parts named.

We have shown in the accompanying drawings, and have described above, the best and simplest embodiment of our invention of which we are now advised. It will be obvious, however, that the generic ideas of the invention may be practised with other forms of mechanism than that herein shown and described, and hence we do not wish to be understood as confining the invention, except as may be indicated in the claims, to the precise construction herein shown and described. 105

We claim:

1. A heel-building machine comprising a 115 heel-blank holder of a length to accommodate a plurality of heel-blanks, and a plurality of means, including a series of dies movable in a horizontal plane, operating, in succession, to cut lifts and deposit them in 120 said holder to form said blanks.

2. A heel-building machine comprising a heel-blank holder of a length to accommodate a plurality of heel-blanks, and a plurality of means operating, in succession, to cut and 125 paste lifts and deposit them in said holder to form said blanks.

3. A heel-building machine comprising a stationary heel-blank holder of a length to accommodate a plurality of heel-blanks, and 130

- 95 a plurality of means including a series of dies movable in a horizontal plane, operating, in succession, to cut lifts and deposit them in said holder to form said blanks.
- 10 5. A heel building machine comprising a heel-blank holder open at both ends and of a length to accommodate a plurality of heel-blanks, and a plurality of means, including a series of dies movable in a horizontal plane, operating, in succession, to cut lifts and deposit them in said holder to form said blanks.
- 15 6. A heel building machine comprising a heel-blank holder of a length to accommodate a plurality of heel-blanks, lift cutting and ejecting means operating to successively cut lifts and deposit them in said holder to form said blanks, and actuating mechanism for effecting the operations of cutting and ejecting lifts.
- 20 7. A heel building machine comprising a heel-blank holder of a length to accommodate a plurality of heel-blanks, and a plurality of means operated by the machine to successively cut lifts and deposit them in said holder to form said blanks.
- 25 8. A heel building machine comprising a heel-blank holder of a length to accommodate a plurality of heel-blanks, a plurality of means operating automatically to cut lifts and deposit them in said holder to form said blanks.
- 30 9. A heel-building machine comprising a heel-blank holder of a length to accommodate a plurality of heel-blanks, a plurality of means operating, in succession, to cut lifts of different size and deposit them in said holder to form said blanks, and means for positioning the lifts so deposited.
- 35 10. A heel-building machine comprising a heel blank holder of a length to accommodate a plurality of heel-blanks, a plurality of means operating, in succession, to cut lifts of different size and deposit them in said holder to form said blanks, and automatically-operating means for positioning the lifts so deposited.
- 40 11. A heel-building machine comprising a heel-blank holder of a length to accommodate a plurality of heel-blanks, a plurality of means operating automatically to successively cut and paste lifts and deposit them in said holder to form said blanks, and automatically-operating means for positioning the lifts so deposited.
- 45 12. A heel-building machine comprising a heel-blank holder of a length to accommodate a plurality of heel-blanks, and a plurality of means operating to successively cut and paste lifts and deposit them in said holder to form blanks, and means operating automatically to render said paste-applying means inoperative at selected intervals of the movement of the machine.
- 50 13. A heel-building machine comprising a heel-blank holder of a length to accommodate a plurality of heel-blanks, and a plurality of means operating automatically in succession, to deposit selected numbers of lifts in said holder to form said blanks, and to separate each series of lifts from a succeeding series of lifts similarly deposited in said holder.
- 55 14. A heel-building machine comprising a heel-blank holder of a length to accommodate a plurality of heel-blanks, lift-cutters movable to a position over said holder, and means for discharging from said lift-cutters and depositing in separated relation in said holder successive series of cut lifts, each series comprising the number of lifts for a heel-blank.
- 60 15. A heel-building machine comprising a heel-blank holder of a length to accommodate a plurality of heel-blanks, a movable carrier, a series of lift-cutters mounted therein and movable thereby in succession to a position over the heel-blank holder, and means for discharging cut lifts from the cutters into the said heel-blank holder in separated series, each series comprising the number of lifts necessary for a heel-blank.
- 65 16. A heel-building machine comprising a heel-blank holder of a length to accommodate a plurality of heel-blanks, a paste-applier, a movable carrier, a series of lift-cutters mounted therein and movable thereby, in succession, to a position over said paste-applier and over said holder, and ejecting mechanism for discharging the cut and pasted lift from each die and forcing it into said holder to form a blank.
- 70 17. A heel-building machine comprising a heel-blank holder of a length to accommodate a plurality of heel-blanks, a paste-applier, a horizontally-rotatable head, a series of dies carried by the head and movable thereby, in succession, to a position over said paste-applier and over said holder, and ejecting mechanism for discharging the cut and pasted lift from each die and forcing it into said holder to form a blank.
- 75 18. A heel-building machine comprising a heel-blank holder of a length to accommodate a plurality of heel-blanks, a paste-applier, a movable carrier, a series of lift-cutters mounted therein and movable thereby, in succession, to a position over said paste-applier and over said holder, ejecting mechanism for discharging the cut and pasted lift from each die and forcing it into said holder, and automatic means for separating

each series of lifts so deposited, and constituting a heel-blank, from a similar and superimposed series.

19. A heel-building machine comprising a heel-blank holder of a length to accommodate a plurality of heel-blanks and of a size to frictionally engage a part, at least, of each heel-blank, and a plurality of means operating, in succession, to cut and paste lifts and deposit them in said holder in separated series, each series comprising the number of lifts for a heel-blank.

20. A heel-building machine comprising a heel-blank holder of a length to accommodate a plurality of heel-blanks, a series of lift-cutters mounted to be moved successively to a position over the heel-blank holder, a plate-carrier interposed in the series of lift-cutters, and means for discharging cut lifts from said lift-cutters, in succession, into said heel-blank holder to form said blanks, and for discharging a plate from said plate-carrier on top of each series of lifts so deposited in the heel-blank holder.

21. A heel-building machine comprising a heel-blank holder of a length to accommodate a plurality of heel-blanks, a horizontally-rotatable head, a series of lift-cutters mounted in the head and movable thereby, in succession, to a position over the heel-blank holder, a plate-carrier mounted in the head at the end of the series of lift-cutters and likewise movable to a position over the heel-blank holder, and means for discharging cut lifts from each lift-cutter, in succession, into said heel-blank holder to form said blanks and for discharging a plate from said plate-carrier on top of the series of lifts so deposited in said heel-blank holder.

22. In a heel-building machine, in combination with a heel-blank holder, a rotatable head, a series of dies carried thereby, means coöperating with said dies for cutting lifts and depositing the cut lifts in the holder, driving mechanism for actuating said means, means supplemental to said driving mechanism for rotating said head after the driving mechanism is at rest, and automatic means for arresting the motion of said head at predetermined positions.

23. In a heel-building machine, in combination with a heel-blank holder, a movable head carrying a series of dies, a cutting block located below said dies, means for raising said block into contact with a die, means for ejecting a cut lift from a die and depositing it in said holder, driving mechanism for actuating said means, and means for moving said head in stages whereby to cause successive pairs of dies to come to rest, the one over said holder and the other over said cutting block.

24. A heel-building machine comprising a holder for heel-blanks and a cutting block, a

rotatable head carrying a series of cutting dies, an ejector device, a driven shaft, means automatically actuated thereby at the will of the operator for raising said cutting block and actuating said ejector device, supplemental means for automatically rotating said head, and automatic means for stopping the movement of said head with one die over said holder and under said ejecting device, and another die over said cutting block.

25. A heel-building machine comprising a rotatable head carrying cutting dies, a ratchet member carried by said head, spring-actuated means for engaging said ratchet to turn the head, and a spring-controlled stop device adapted to be turned into engagement with said ratchet to arrest the movement of the head at predetermined positions.

26. In a heel-building machine, in combination with a heel-blank holder, a rotatable head, a series of dies carried thereby and movable by said head in succession to a position over said holder, a cutting block for co-operating with said dies, an ejector device, driving mechanism, means actuated thereby at the will of the operator for raising said cutting block and for actuating said ejector device to discharge lifts from said dies, spring-controlled means for rotating said head, and automatic means for arresting the movement of said head at predetermined positions.

27. A heel-building machine comprising a heel-blank holder of a length to accommodate a plurality of heel-blanks, a series of lift cutters, and means coöperating therewith to successively cut and deposit lifts in said holder to form said blanks.

28. A heel building machine comprising a heel-blank holder of a length to accommodate a plurality of heel-blanks, a series of lift-cutters movable in succession to a position over said holder, and means coöperating therewith to successively cut lifts and deposit them in said holder to form said blanks.

29. A heel-building machine comprising a heel-blank holder of a length to accommodate a plurality of heel-blanks, a series of dies movable in succession to a position over said holder, lift cutting, pasting and ejecting means coöperating with said dies, and means for actuating the same whereby to successively cut and paste lifts and deposit them in said holder to form said blanks.

30. A heel-building machine comprising a heel-blank holder of a length to accommodate a plurality of heel-blanks, each blank comprising an assemblage of lifts, a series of dies and a separator movable in succession to a position over said holder, lift cutting and pasting means coöperating with said dies, and an ejector coöperating with said dies and with said separator.

31. A heel-building machine comprising a

heel-blank holder of a length to accommodate a plurality of heel-blanks, each blank comprising an assemblage of lifts, a series of dies and a separator movable in succession to a position over said holder, lift cutting and pasting means coöperating with said dies, an ejector located over said holder and adapted to coöperate with said dies and said separator, a driven shaft, means actuated thereby at the will of the operator to operate said lift-cutter, paster, and ejector, and means for effecting a movement in stages of said dies and separator.

32. A heel-building machine comprising a heel-blank holder of a length to accommodate a plurality of heel-blanks, each blank comprising an assemblage of lifts, a series of dies and a separator movable in succession to a position over said holder, lift cutting and pasting means coöperating with said dies, an ejector located over said holder and adapted to coöperate with said dies and said separator, a driven shaft, means actuated thereby at the will of the operator to operate said lift-cutter, paster, and ejector, and automatic means for effecting a movement in stages of said dies and separator.

33. A heel-building machine comprising a heel-blank holder of a length to accommodate a plurality of heel-blanks, each blank comprising an assemblage of lifts, a movable member, a series of dies and a separator carried by said member, automatic means for moving said member to bring all of said dies and said separator successively to a position over said holder, automatic means for arresting the movement of said member to effect such successive positions of said dies and separator, lift cutting, pasting, and ejecting means coöperating with said dies, a driven shaft, and means actuated thereby at the will of the operator for operating said lift cutting, pasting and ejecting means.

34. In a machine of the class described, in combination with a holder embodying a breast-plate, a lift carrier, a reciprocating ejector coöperating therewith, pivoted arms mounted at opposite sides of said holder and movable by said ejector to cause their free ends to engage the sides of and position each lift deposited in said holder, a spring-actuated arm having a free end adapted to engage the rear edge of each lift, and means actuated by said ejector in one movement to retract said arm against the resistance of its spring, and in the opposite movement to release said arm to permit it to forcibly strike the deposited lift a sudden blow to force it against said breast-plate.

35. In a heel-building machine, in combination with a heel-blank holder, a rotatable head carrying a series of dies, a vertically-movable cutting block located below said dies, a reciprocating ejector positioned over said holder, a driven shaft, means actuated

thereby at the will of the operator for raising said cutting block and reciprocating said ejector, means for rotating said head independently of the movement of said shaft, and automatic means for arresting the movement of said head with one die over said cutting block and another die over said holder.

36. In a heel-building machine, in combination with a heel-blank holder, a rotatable head carrying a series of dies, a vertically-movable cutting block, a reciprocating ejector located over said holder, a ratchet wheel carried by said head, a spring, a member controlled thereby and coöperating with said ratchet wheel, a driven shaft, means actuated thereby at the will of the operator for raising said cutting block and reciprocating said ejector, means carried by said ejector to move said member against the resistance of its spring into operative engagement with the said ratchet wheel in the movement in one direction of said ejector, and to release said member and thereby permit its spring to act to turn said ratchet wheel and rotate said head in the movement in the other direction of the ejector, and automatic means for arresting the movement of said head with one die over the cutting block and another die over said holder.

37. In a heel-building machine, in combination with a die, a rotatable and vertically-movable cutting block located below the same, means for raising and then releasing said cutting block, and means for causing the rotation of said cutting block in its fall after such release.

38. In a heel-building machine, in combination with a die, a cutting block yieldably supported beneath the die, and depressible to increase the space between it and the die, and means for actuating said cutting block.

39. In a heel-building machine, in combination with a die, a rotatable and vertically-movable cutting block yieldably supported beneath the die and depressible to increase the space between it and the die, and mechanism for raising and releasing said cutting block.

40. In a heel-building machine, in combination with a die, a rotatable and vertically-movable cutting block located below the same, means for raising and then releasing said cutting block, and means adapted to be engaged by said cutting block in its fall after said release to cause it to be rotated.

41. In a heel-building machine, in combination with a die, a rotatable and vertically-movable cutting block located below the same, means for raising and then releasing said cutting block, a pivoted arm having a free end engaging the under side of said cutting block, and a spring tending

- normally to force such free end into such engagement whereby as the cutting block falls after its release it will be given partial rotation by engagement with the free end of said member.
42. In a heel-building machine, in combination with a rotatable die carrier, and lift cutting and ejecting means coöperating therewith, a driven shaft, mechanism actuated thereby at the will of the operator for operating said lift cutting and ejecting means, means for rotating said die carrier in stages, and a safety device for preventing actuation of said lift cutting and ejecting mechanism while said die carrier is in motion.
43. In a heel-building machine, a rotatable die carrier, lift cutting and ejecting means coöperating therewith, a driven shaft, mechanism for actuating said lift cutting and ejecting means, a clutch for operatively connecting said mechanism with said driven shaft, a clutch-actuating device, a member rotatable with said die carrier and having a circular series of apertures on its under side, a rod operatively connected with said clutch-actuating device and adapted to be elevated thereby, and automatic means for arresting the movement of said die carrier with one of said apertures over the end of said rod whereby when the clutch-actuating device is operated it will cause said rod to enter such aperture, while in any other position of the parts the end of said rod will engage the under side of said member and prevent the movement of said clutch-actuating device.
44. In a heel-building machine, a rotatable die carrier, lift cutting and ejecting means coöperating therewith, a driven shaft, mechanism for actuating said lift cutting and ejecting means, a clutch for operatively connecting said mechanism with said driven shaft, a treadle shaft for actuating said clutch, a member rotatable with said die carrier and having a circular series of apertures on its under side, an arm carried by said treadle shaft, a rod pivotally connected therewith and adapted to be elevated thereby, and automatic means for arresting the movement of said die carrier with one of said apertures over the end of said rod whereby when the treadle shaft is turned to actuate the clutch said rod will enter into such aperture, while in any other position of the parts the end of said rod will engage the under side of said member and prevent the movement of the treadle shaft.
45. In a heel-building machine, in combination with a rotary die carrier, and lift cutting and ejecting means coöperating therewith, means for positively actuating said lift cutting and ejecting means, supplemental actuating mechanism for rotating said die carrier after each movement of the
- lift cutting and ejecting means, and means for automatically arresting the movement of said die carrier at stated intervals.
46. In a heel-building machine, in combination with lift cutting and ejecting mechanism, and means for operating the same simultaneously, an independently-movable die carrier coöperating with said lift cutter and ejector, and automatic means for arresting the movement of said die carrier with two of its dies in operative relation, respectively, with said lift cutter and ejector.
47. In a heel-building machine, in combination with a vertically-movable cutting block, a head mounted above the same and carrying a series of dies, said dies being movable by said head, in succession, to a position over said cutting block, means for raising said cutting block into contact with the successive dies, and automatic means for rotating said head after each movement of the cutting block.
48. In a heel-building machine, in combination with a movable head carrying a series of dies, a cutting block located below said dies, means for raising said block into contact with a die, and means for moving said head in stages whereby to cause the dies to come to rest in succession over said cutting block after each movement of the latter.
49. A heel-building machine comprising a heel-blank holder, a paste-applier, a movable carrier, a series of lift-cutters mounted therein and movable thereby, in succession, to stationary positions over said paste-applier and over said holder, means for actuating said paste-applier while a die is stationary above the same, and ejecting mechanism for discharging the cut and pasted lift from each die and forcing it into said holder.
50. A heel-building machine comprising a heel-blank holder, a paste-applier, a movable carrier, a series of lift-cutters mounted therein and movable thereby, in succession, to positions over said paste-applier, and over said holder, ejecting mechanism for discharging the cut and pasted lift from each die, and forcing it into said holder, and means for actuating said paste-applier from said ejecting mechanism.
51. A heel-building machine comprising a heel-blank holder of a length to accommodate a plurality of heel-blanks, a series of dies movable, in succession, to a position over said holder, lift-cutting, pasting and ejecting means coöperating with said dies, a driven shaft, means actuated thereby, at the will of the operator, to operate said lift cutter, paster and ejector, and means for effecting a movement in stages of said dies.
52. A heel-building machine comprising a heel-blank holder of a length to accommodate a plurality of heel-blanks, a series of dies movable, in succession, to a position over said holder, an ejector for said dies

cated over said holder, a cutting-block and a paster coöperating with said dies, means for effecting a movement in stages of said dies in such manner that they will come to rest with dies located, respectively, over said cutting-block, paster, and holder, a driven shaft, and means actuated thereby, at the will of the operator, to operate said cutting-block, paster and ejector at such time as the dies are stationary and in operative relation therewith.

53. In a heel-building machine, in combination with a series of movable dies, and means adapted to coöperate with each die 15 for cutting a lift, an indicator, and means carried by each die to actuate said indicator as a lift is cut by the die to indicate the thickness of the cut lift.

54. In a heel-building machine, in combination with a rotatable head carrying a series of dies, means coöperating with said dies for cutting lifts, an indicator, and means carried by each die and adapted to actuate said indicator as a lift is cut by the die to 25 indicate the thickness of the cut lift.

55. In a heel-building machine, in combination with a movable cutting block, a rotatable head carrying a series of dies, means for actuating said head to bring its dies in succession to a stationary position over said cutting block, means for raising said cutting block into contact with each die, an indicator, and means carried by each die to actuate said indicator as the lift is cut to indicate the thickness of the cut lift.

56. In a heel-building machine, an indicator, a series of dies movable, in succession, to coöperative relation with said indicator, means adapted to coöperate with each die for cutting a lift, and means carried by each die for actuating said indicator as a lift is cut to indicate the thickness of the cut lift.

In testimony whereof, we have hereunto set our hands in presence of two subscribing witnesses.

JOHN E. MITCHELL.
DENNIS PARKS.
